(57) **CLAIM**

The ornamental design for a computer mouse, as shown and described.

DESCRIPTION

FIG. 1 is a perspective view of a computer mouse showing our new design;

FIG. 2 is a top plan view thereof;

FIG. 3 is a left side elevational view thereof;

FIG. 4 is a right side elevational view thereof;

FIG. 5 is a front elevational view thereof; and,

FIG. 6 is a rear elevational view thereof.

The unshown bottom of the computer mouse forms no part of the claimed design. The broken line showing of the buttons on the sides and the wheel and its surrounding region is for illustrative purposes only and forms no part of the claimed design.
